UNITED STATES PATENT OFFICE

2,459,071

SLIDING VANE AIR COMPRESSOR AND EXHAUSTER

Harry A. Garrison, Minneapolis, Minn., assignor of one-half to Joe F. Schwan, St. Paul, Minn.

Application September 8, 1945, Serial No. 615,152

6 Claims. (Cl. 230—153)

1

My invention relates to a rotary air compressor and exhauster and has for its object to provide in combination a gas compressor which also may be used as an exhauster for producing vacuum wherein a cylindrical rotor carries radially movable piston members, said rotor and members being mounted within a chamber whose outer surface is not circular in cross-section but is made up of a composite curve embodying in parts circular arcs concentric with the center of the rotor and in other parts non-circular arcs which are not concentric and which follow substantially the lines of an Archimedian spiral.

In connection with rotary compressors also used to produce high degrees of vacuum, the principle in general is to have a radially movable piston member operated by a cylindrical rotor within a cylindrical casing which is of larger diameter than the diameter of the rotor and has its central axis eccentric to the axis of the rotor. This leaves an elongated crescent-shaped chamber surrounding the rotor, one side of which has admitted thereto gas or air (or for that matter liquid fluid) at normal or vacuum pressures, and the other side of which receives this volume of gas or other fluid, and which, in front of the piston, is compressed and discharged through an opening or openings against the pressure of the fluid into which it is discharged—either that of the compressed gas or the normal pressure of air when the device is used for producing vacuum.

There is thus in this form of apparatus always a differential pressure between the pressure side and the intake side of the compressor which difference may be very high with either high compression of gas or very low vacuum.

Because of this fact, the compression or evacuation of gas there is, of course, a strong tendency toward back pressure leakage past the contacting part of the radially moving rotating pistons from the pressure side to the intake side of the device. The pistons may have quite extensive plane faces engageable with side walls, which, with an appropriate oil film, will effectively resist this tendency and prevent cross leakage.

The problem has always been to prevent leakage where the ends of the pistons engage the circular wall of the pumping chamber. The reason for this is that it has been found to be impractical or impossible to have any considerable extent of surface engaging the curved surface of this back wall.

This application is an improvement of and an

2

advance over my Patent No. 2,046,873, granted July 7, 1936.

In that patent I proposed to remedy the above-noted difficulty by forming the chamber within which the pistons operate not as truly circular in cross-section, but as made up in a series of arcs of circles "excentrically disposed . . . in such manner as to cause a gradual merging" between the several circular arcs. I also formed the piston with ends which were curved in an arc corresponding to the curvature of the arc bounding the center wall of the pumping chamber at its widest part to give long contact at that point.

15. This arrangement has proved very effective for pumping liquid such as water, for which it was primarily designed. But in pumping gas for high compression or a high degree of vacuum the face of the piston in each case is tipped so there is substantially little more than a line contact along the important compression arc where leakage is most likely to take place.

Another serious difficulty which has been encountered in connection with rotary compressors and evacuators for various gases, has been that where the rotor is rotated at high speed there has resulted a great deal of unpleasant noise, usually in the form of a throbbing or thumping effect and this noise has generally 25 been accompanied and probably caused by leakage of gas from the pressure to the intake sides of the rotating pistons.

I have discovered a manner of curving the inside walls of the pumping chamber which is not in cross-section circular or made up entirely of circular arcs, but in which the essential curves at the inlet side and particularly at the compression side of the pumping chamber follow the lines of an Archimedian spiral, so, when pistons 35 having a multiplicity of appropriate curves thereon are employed, a substantial area of contact between the piston ends and such curved walls may be effected.

I have discovered also that, by forming the 45 piston members with ends considerably wider than heretofore has been deemed desirable, and forming on the ends of said piston members three sets of curves corresponding to the sets of curvatures of the inner walls of the pumping chamber, I am able to maintain an extensive 50 area of contact between the piston ends and the walls of the pumping chamber throughout the entire rotation of the pumping pistons.

I have also discovered that, if the pistons extend in opposite directions so as to have their

ends engage the walls of the pumping chamber in opposite directions, by making said pistons sectional and providing spring means forcing them in opposite directions, a very firm and certain contact between the appropriate curved portions of the piston ends and of the inner walls of the pumping chamber may be maintained at all times, even when the rotor carrying the pistons is being rotated at very high speed, and the unpleasant throbbing and thumping will be almost entirely eliminated.

It is a principal object of my invention, therefore, to provide a cylindrical rotor having guideways extending radially through the same, in which operate radially movable piston members carried about the axis of the rotor with the rotor, inside of a pumping chamber of substantially larger cross-sectional area than the cross-sectional area of the rotor, and wherein the inner walls of the pumping chamber and the outer ends of the pistons are severally provided with cooperating and differently curved surfaces such that there will at all times be an extended area of contact transversely between the ends of the pistons and the inner surface of the pumping chamber.

It is a further object of my invention to provide a cylindrical rotor eccentrically mounted within a pumping chamber, so as to form a crescent-shaped pumping chamber proper, whose inner walls comprise circular concentric arcs contacted on one side by the rotor and most widely spaced on the other side from the rotor and whose inner walls extend between the above-noted arcs substantially along the lines of an Archimedean spiral.

It is a further object of my invention to provide radial slots extending through the body of the rotor and to mount in said slots radially movable piston members of considerable width and to form on the ends of said piston members sets of three curves each, the inner of which will be in the circular arc of the rotor and of the outer wall of the pumping chamber where the two contact, and will be concentric with the circular arc of the outer wall of the pumping chamber diametrically opposed thereto, the other two curves of the ends of the pistons at each side of the circular curves being that of the respective Archimedean spiral curves extending between the above-named circular arcs, which will thus effect extended transverse area of contact between the ends of the pistons and all parts of the inner walls of the pumping chamber.

It is a further object of my invention to provide the pumping chamber proper with a series of inlet openings leading through the walls thereof and connected with any suitable source of gas either for compressing the same or for evacuating a chamber, and to provide one or more openings from the compression side of the pumping chamber through which the compressed gas will be driven either to a receiver thereof where compression is then sought, or to atmosphere where evacuation is being effected.

It is a further object of my invention to provide radial channels within the body of the rotor which extend diametrically across the same, and to mount in said channels pistons movable radially within the rotor, which occupy and substantially fill both ends of said channels but which are separated into two sets, slideable relatively to the sets as such and to each piston part of each set, to effect a complete engagement of the appropriate parts of said pistons with the inner walls

of the pumping chamber throughout the movements of said pistons as the rotor is rotated.

The full objects and advantages of my invention will be apparent in connection with the description of its structure and mode of operation given in the appended specification, and the novel features of my invention as combined to produce the aforesaid advantageous results will be particularly pointed out in the claims.

10 In the drawings illustrating an application of my invention in one of its forms:

Fig. 1 is a plan view of the invention with the cover member removed and showing some parts broken away and in section.

15 Fig. 2 is a sectional view taken on line 2—2 of Fig. 1.

Fig. 3 is a sectional view taken on line 3—3 of Fig. 1.

20 Fig. 4 is a sectional view taken on line 4—4 of Fig. 1.

Fig. 5 is a sectional view taken on line 5—5 of Fig. 1.

Fig. 6 is a sectional view taken on line 6—6 of Fig. 1 with some parts broken away and omitted.

25 Fig. 7 is a similar sectional view taken on line 7—7 of Fig. 1.

Fig. 8 is a front elevation view of the rotor showing the guide channels of the radially movable piston.

30 Fig. 9 is an enlarged view of one of the piston ends showing the character of curve at such ends.

As shown, my device embodies a main frame casting 10 which includes an annular flange member 11. This flange, with a cover plate later described, encloses a cup-shaped chamber portion 12.

35 From the chamber 12 extends a depressed part 13 circular in cross-section, said depressed part, shown in Fig. 5 and in dotted lines in Fig. 3, having its center eccentric in a diametric line with respect to the inner walls 14 of the chamber 12.

40 The casting 10 is provided with a boss 15, Fig. 5, which has through it a circular opening 16 concentric with the axis of the depressed portion 13. In the opening 16 is a shaft 17 adapted to be connected at 18, in any well-known way, with means for rotating the shaft. The other end of shaft 17 has integrally connected therewith a 45 rotor 19 which is shown in both Figs. 1 and 5.

45 The rotor comprises a supporting member 20 fitted and operative within the depressed portion 13. This member 20 is integral with shaft 17. Within the chamber 12 and formed integral 50 with member 20 are sections 21, 22, 23 and 24 of the rotor proper, as shown clearly in Figs. 1 and 8.

55 The face of the rotor is provided with two transverse channels 25 and 26, these channels being rectangular in cross-section as shown and being closed by a face plate 27. This plate has its inner surface milled and ground and smoothed to a true plane, and the outer edges 28 of the flange member 11 also are ground in a true plane.

60 A series of bosses 29 are cast on the outside of the flange member 11 and are provided with bolt holes. Set bolts 30 are screwed into these holes, thus holding the plate 27 in firm metal to metal sealing contact with the edges of the flange member 11, and completely enclosing the chamber 12.

65 The rotor thus operates within that chamber between the opposed faces of the casting 10 and the plate 27.

70 All of the foregoing faces are finished with plane surfaces so a close contact is secured. Actually there will be some slight tolerance, as, for

example, one one-thousandth to two one-thousandths of one inch. By any known and suitable oiling method, not shown, a film of oil will be established between all of these edge surfaces of the pistons, effecting a complete seal against the possibility of air leakage between such surfaces.

This is made possible and certain because such large areas of surface are together, and the oil film extending over such large areas will be able to wholly prevent leakage regardless of the pressures built up at any point. Some little tolerance is necessary, of course, to prevent striking of the pistons, hereinafter described, operative in the channels 25 and 26, particularly when slight expansion occurs from heating. Tests have shown that the rotor operates fully and with relative small consumption of power, in the arrangement above outlined, with very small consumption of oil.

As clearly shown in Fig. 1, there is a space, crescent-shaped in cross-section, which is between the outer surface 31 of the rotor 19 and the inner face 14 of flange 11, with the rotor rotating in the direction of the arrows. This crescent-shaped space may be divided into four parts: an intake part 32 extending substantially from its beginning at about 33 to its termination at about 34, a compression part extending from about 35 to its ending about the point 36, a sealing part between 33 and 36 where the outer rotor wall 31 substantially contacts the inner flange wall 14 at 33 and a neutral part between 34 and 35 which affects neither inlet nor compression.

The inlet gas will enter the inlet part 32 through a multiplicity of apertures 37, coming from any suitable source out of a chamber 38 indicated in part as with a casing 39, not shown. The gas goes into the compression chamber, which may be designated as 40. The gas received from the neutral position between 34 and 35 is steadily compressed until it is forced out of the outlet opening 41 through nipple 42, which may be either connected with a container for compressed gas or go to atmosphere as may be desired. Another and smaller opening 43 may connect by pipe 44 with the boss 41 to prevent any tendency toward thumping, resulting from forcing the compressed gas through a single opening.

The formation of the curve of the inner surface of the flange 11 is a highly important feature of my invention. This curve between the points 33 and 36 will be the arc of a circle having its center at 45 which is the axis of the rotor 19. This curve of the inner surface of flange 11 will be, therefore, that or substantially that, of the outer surface of rotor 19.

The curve between points 34 and 35 is likewise the arc of a circle struck from the center 45 at the axis of the rotor, and hence is not only spaced from but is concentric with the outer surface of the rotor. This curve 34—35 has greater radial angularity at its ends than is true of the curve 33—36 to give an addition in length equal to twice the width of the center curve at the end of the piston.

From 35 to 36, on the compression side, and from 34 to 33, on the inlet side, the curve of the inner wall of the pumping chamber is not in the arc of a circle but is a curve with a constantly varying radius vector, which, in each instance, connects the ends of the arc curve at 35 and 34 respectively with the ends of the arc curve at 36 and 33 respectively along substantially the line of an Archimedean spiral.

While the actual dimensions of the chamber formed inside of the flange portion 11, on lines taken through the substantial center of that chamber are such that the chamber as a whole will be wider transversely of its position in Fig. 1, than it is perpendicularly in reference to that figure, the contact distances between the portions of the heads in actual engagement with the outer walls of this chamber are the same throughout the entire circumferential extent of those outer walls. These distances do not go through the center of the rotor 22 but in each instance are chords offset from said center so as to pass substantially through the centers of the opposed contact surfaces at the end of the pistons.

However, since there may be some expansion of the piston members from heat and for other reasons, I have found that better results are obtained by making the piston members in each instance separate members thrust outwardly by springs, rather than each a single piston member, as in my former patent.

This has two important effects. First, it increases the aggregate cross-sectional area and cubical contents of the compression chamber, and the inlet chamber, thus giving greater volume for a given size rotor, and it produces the form of curve heretofore defined, which in conjunction with the three types of curves at the ends of the pistons enables an extensive area of actual contact between the ends of the pistons and the inner walls of these chambers to be established at all times.

Although the channels 25 and 26 in which the pistons operate extend across each other at right angles radially through the center of the rotor, and are the same length, even though the operative extent of piston lengths in these channels are the same, I do not make the piston member as a unit extending through each channel but form each piston member in two parts adapted to move longitudinally relatively the one to the other, but operating in the same identical channels, and having the same identical cross-sectional areas at their operative ends.

In addition to the action of centrifugal force, which tends to maintain the piston ends in contact with the inner walls of the pumping chamber, spring means are also provided to make certain that there is constant contact between the respective piston ends and said outer wall, to control relative longitudinal movements thereof, to compensate for expansion from heat, and also to compensate for any wear of the piston contact surfaces.

As clearly shown in Fig. 4, the main body of each of the pistons comprises a head designated by the numeral 46, which, as clearly shown in Fig. 4, is rectangular in cross-section. In Fig. 4 this is shown as square in cross-section, but obviously it may be an elongated rectangle if it is desired to have pistons of greater width than would be comprised in a rectangular square.

Each of the several heads 46 has formed at the inner end thereof a rectangular finger which has a cross-sectional area of actually one-fourth of the full cross-sectional area of the head. These fingers and their relation to one another are clearly shown in Fig. 5 and are designated respectively as 47, 48, 49 and 50.

The four of them lie together at the center in two crossing layers, the bottom layer 47, 48 and the top layer 49, 50, as shown in their diagonal extent in Fig. 5. The bottom layer 47, 48 lies underneath the top layer 49, 50, Fig. 6, and

the top layer 49, 50 overlies the bottom layer 47, 48, Fig. 7. They cross at the center, as shown in Fig. 5, directly at right angles, and are relatively movable with respect to the members of each pair and with respect to each pair of members to the other pair.

Each of the fingers is provided with a socket 51 in its end, as clearly shown in Figs. 1, 2 and 3. Within each of the sockets is a coiled compression spring 52, as clearly shown. It will be apparent, therefore, that each pair of piston members 47, 48 and 49, 50, respectively has a pair of springs operative to mutually force the piston heads 46 against the inner wall 14 of the pumping chamber 10. These parts are thus held in the guide slots for longitudinal movement. Continually there is added to the action of centrifugal force the constant pressure of two springs 52, urging the faces of the body of the pistons 46 against the inner wall 14 of the pumping chamber.

The nature of heads 46 is shown in Fig. 1 and in enlarged scale in Fig. 9. The end of each head is provided with a central curved portion 53 and other curved portions 54 and 55 on each side of the curved portion 53. The curved portion 53 is the arc of a circle struck from the center 45 of the rotor and having the same radius as the rotor and thus is adapted to engage with its whole surface the arc 33-36 at one part of its movement, and to engage the arc 34-35 with a substantial part of its surface at the other part of its movement.

Each of these arcs 33-36 and 34-35 are concentric. It follows that while there is complete contact of the curved portion 53 across the whole of arc 33-36, there will be something less than complete contact of these arcs across the arc 34-35.

This is not important, however, since the cross-sectional area of the pumping chamber between 34-35 does not change substantially from end to end and consequently there is little or no differential pressure on opposite sides of the piston along this stretch of the pumping chamber, and leakage is easily prevented.

On the other hand, the pressure differential between the points 33-36 along the circle arc there is at substantially the highest point and hence the complete contact of the portion of the curve 53 on the ends of piston members 46 effects complete sealing along this critical area.

An important feature of the invention is that while arc 34-35 and arc 33-36 are made on circles whose diameters differ, the angular length of the arc 34-35 is greater than the angular length of the arc 33-36 by a specific distance. As previously explained, and as clearly shown in Fig. 1, the angular length of arc 34-35 is equal to the angular length of arc 36-33 plus twice the width of the central curve 53 on the end of each of the pistons 46. Thus a first line A-B drawn from point 36 through the center 45 of rotor 19, and a second line C-D drawn from the point 33 through the center 45 of rotor 19 will each be separated from the points 34 and 35 by the distance designated at 53a which is equal to the width of the curve 53 on the end of each of pistons 46. In this manner, when the curve 53 on the end of one of the pistons has completely entered arc 34-35, a similar curve on the end of a diametrically opposite piston will commence to enter arc 36-33 to thereby prevent leakage past the ends of these two oppositely disposed pistons when they are in the critical position of

sealing the low pressure side 32 from the high-pressure side 40. Since arc 34-35 is longer than arc 36-33 by twice the width of curve 53, the sealing relationship will continue until the curve 53 on the end of the piston contacting arc 36-33 has cleared point 33.

Furthermore, when curve 53 on one end of the piston structure has cleared point 33, curve 53 on the other end of the piston structure will be between the line C-D and point 35. Thereafter, as curve 55 on the first end of the piston structure begins to contact the non-circular curve 33-34, curve 54 on the other end of the piston structure makes full contact with the other non-circular curve 35-36, until the point 36 is reached and passed, at which time the curved portion 55 on the first end of the piston structure has initially reached point 34, thereby providing a continuous seal between opposite lateral sides of each piston and continuous longitudinal control of the pistons during a complete revolution of the rotor. The curves at the ends of the pistons, designated as 54 and 55, respectively, as clearly shown in Figs. 1 and 9, follow the same lines of the Archimedean spiral as the curves of the inner walls of the compression chamber 40 and the inlet chamber 32. When the piston end leaves the arc 34 and 35 it will be tipped, as shown at 56 in Fig. 1, bringing the arc curve 53 out of contact with the wall of the compression chamber 40 and at the same time bringing the curve 54 into contact with the stretch of compression chamber wall 35-36.

Since the curve 54 corresponds to the curve 35 of the stretch of compression chamber wall 35-36, as the piston is carried forward in its slot, moving inwardly while the companion piston moves outwardly, the curved portion 54 will, throughout its length, contact the inner wall 14 of compression chamber 40 and will continue to do so until the point 36 has been reached and passed, when the piston head again will be rocked relatively to the arc section 33-36 and the central arc curve 53 will there contact and seal that section.

Following this, when the piston passes the point 33 it will still further rock relatively taking the curve 53 out of contact with the wall of inlet cylinder 32 and swinging the curve 55 on the opposite side of the piston into engagement with the curve extending along the inner wall of inlet chamber 32.

This operation will be continuously repeated by each of the four piston ends producing an important and heretofore unsecured result of a constant contact of a substantial area of the piston head with all parts of the curved walls of the pumping chamber.

I claim:

1. In a rotary compressor, a cylindrical rotor, a casing surrounding the rotor of greater cross-sectional area than that of the rotor, said rotor having a portion contacting the circumferential wall of the casing so as to leave a generally crescent-shaped pumping chamber between the outer wall of the rotor and the inner wall of the casing, said inner wall having its cross-sectional curvature partly in arcs of a circle and partly in non-circular curves, and pistons carried by the rotor and movable outwardly relative thereto to contact the inner wall of the pumping chamber, each of said pistons having a multiplicity of curved contact faces at each end which respectively contact the differently curved areas of the inner walls of the chamber, whereby large areas

of contact between the piston heads and the chamber walls are secured throughout the movement of the piston heads about the full surrounding extent of said contacted walls.

2. In a rotary compressor, a cylindrical rotor, a casing surrounding the rotor of greater cross-sectional area than that of the rotor, said rotor having a portion contacting the inner circumferential wall of the casing so as to leave a generally crescent-shaped pumping chamber between the outer wall of the rotor and the inner wall of the casing, said inner wall having portions of its cross-sectional curvature in the region where the rotor makes contact and diametrically opposite to that region in arcs of a circle and having the intervening parts of its cross-sectional curvature in non-circular curves, and pistons carried by the rotor and movable outwardly relative thereto to contact the inner wall of the pumping chamber, each of said pistons having a multiplicity of curved contact faces at each end, one of said faces curved to contact the arc areas of the inner wall of the chamber and the others of said faces curved to match the non-circular curved faces of the inner wall thereof to secure large areas of contact between the end of the piston and the non-circular curved faces.

3. In a rotary compressor, a cylindrical rotor, a casing surrounding the rotor of greater cross-sectional area than that of the rotor and contacting the rotor at one area, said casing having spaced parallel walls and a circumferential wall perpendicular thereto, the inside surface of said circumferential inner wall comprising a circular arc curved portion at the area of contact and another arc portion of greater radius diametrically opposed thereto and having non-circular curved portions extending between the respective adjacent sets of ends of the curved arc portions, said non-circular portions being curved along the line of an Archimedian spiral, said rotor being provided with a radial slot, and a piston movable endwise in said slot and having a head with three curved contacting faces thereon to engage successively all the curves of said circumferential wall as the rotor is rotated.

4. In a rotary compressor, a cylindrical rotor, a casing surrounding the rotor of greater cross-sectional area than that of the rotor and contacting the rotor at one area, said casing having spaced parallel walls and a circumferential wall perpendicular thereto, the inside surface of said

circumferential inner wall comprising a circular arc curved portion at the area of contact and another arc portion of greater radius diametrically opposed thereto and having non-circular curved portions extending between the respective adjacent sets of ends of the curved arc portions, said non-circular portions being curved along the line of an Archimedian spiral, said rotor being provided with a radial slot, a piston movable endwise in said slot and having a head, said head being formed with a central circular arc curve and other curves following the line of an Archimedian spiral at each side of the central curve to engage successively all of the curves of said circumferential wall as the rotor is rotated.

5. In a rotary compressor, a cylindrical rotor having a radial slot therein, and a piston member movable endwise in said slot, said piston having a head portion with three curved faces on the outer end thereof.

6. A rotary compressor, comprising a cylindrical rotor, a piston carried by said rotor and movable diametrically relative thereto, said piston on each of its opposite outer ends having a central curved portion and other curved portions on each side of the central curved portion, and a casing surrounding said rotor having an inner wall with a first portion and a portion oppositely disposed therefrom being formed of non-circular curves and a second portion and a portion diametrically opposed thereto being formed as arcs of circles whose diameters differ, the angular length of one of said arcs being greater than the angular length of the other arc by substantially twice the length of the central curved portion on the ends of said piston to thereby provide both a continuous seal between the central curved portion of the piston and the arcuate portions of the casing and to assure continuous contact between one of the other curved portions at each end of the piston and the oppositely disposed non-circular portions of the casing.
